UNITED STATES PATENT OFFICE

118,535

DESIGN FOR A DRESS

Jack Wasserman, Lawrence, N. Y.

Application November 25, 1939, Serial No. 88,473

Term of patent 3½ years

To all whom it may concern:

Be it known that I, Jack Wasserman, a citizen of the United States and a resident of the city of Lawrence, in the county of Nassau and State of New York, have invented a new, original, and ornamental Design for a Dress, of which the following is a specification, reference being had to the accompanying drawing, forming a part thereof.

Fig. 1 is a front view of a dress showing my new design.

Fig. 2 is a rear view of the dress shown in Fig. 1.

The characteristic feature of my design resides in the combination on the dress disclosed of the specific air tucking on the waist, yokes and back portions as shown.

I claim:

The ornamental design for a dress, substantially as shown and described.

JACK WASSERMAN.
